UNITED STATES PATENT OFFICE

BENJAMIN F. GRENNAN, OF NEW YORK, N. Y., ASSIGNOR TO EAGLE PENCIL COMPANY, OF NEW YORK, N. Y., A CORPORATION OF DELAWARE

FLAT DROP KNIFE

Application filed August 18, 1927. Serial No. 213,720.

This invention relates generally to pocket cutlery and has particular reference to improvements in the mechanism for opening and closing devices of the character indicated.

One object of the invention is to provide, in a pocket knife of the type having blades movable substantially endwise in and out of a handle, a latching mechanism which will securely hold the blade in either the opened or closed position and which is unlikely to get out of order.

Another object is to provide a general organization which, while adaptable to other forms, is particularly valuable in connection with pocket knives of the popular flat type.

Still another object is to provide a construction in which the blade or a blade-carrying element is so guided and supported that it may move freely to the inner and outer positions with respect to the handle, but which will at the same time prevent excessive angular movement of the blade with respect to the handle when the blade is being used for cutting purposes.

While the invention is particularly suitable for use in pocket cutlery, it is, as will later be clearly apparent, capable of use in connection with other devices such as pencils and similar instruments.

With the foregoing and other objects in view, the invention consists in a novel construction and combination of parts, the novel features of which are pointed out in appended claims, and an embodiment of which, suitable for illustrating the invention, is shown in the drawings accompanying and forming a part of this application.

In said drawings:

40 Figs. 1 and 2 show respectively what may for convenience be termed side and edge views of one form of the improved knife, with the top part of the latter in cross section.

45 Fig. 3 is a side view of the knife with parts broken away to show how the blade is latched in its inner position.

50 Fig. 4 is similar to Fig. 3, but shows how the blade is latched in its outer or cutting position.

Fig. 5 is a section on the line 5—5 of Fig. 3.

Fig. 6 is a detail of the finger piece for operating the blade latch.

Fig. 7 is a cross section through a form of latch having the finger-piece formed integral with the latch.

Fig. 8 is a full side view of the latch referred to in the description of Fig. 7.

The knife shown in the drawings is one of the kind known in the trade as a drop knife, that is, the blade moves in or out by gravity. It is also of the flat type which is so popular in the pocket cutlery field.

The knife handle 10 is a hollow shell of any desired material provided with a slot 11 in one end and an opening 12 in one of its edges or sides. The opposite end of the shell is closed by a cap 13 held in place as hereinafter described.

Within the handle 10 is a shell 16 which is wedged at one end in the tapered portion 17 of the handle and carries at its other end an extension 18 of sufficient width to fit tightly within the cap 13. The extension 18 lies flat against one of the sides of the cap 13 (see Fig. 2) and is provided with a slot 21 which is engaged by one of the in-turned ends 20 of a bow 231, said in-turned ends also extending through circular holes in the handle 10 and cap 13. It is apparent that the bow 20 serves to hold the handle 10, cap 13 and shell 16 together and that the shell is firmly held in position in the handle.

The shell 16 is of sufficient size and is of such shape on its interior as to form a guide for an element 22 carrying a blade portion 23. Corrugations 24 formed inward in the shell 16 may be used to guide the element 22 in such a way as to limit the latter to substantially endwise movement.

One edge of the shell 16 is cut away as at 26 and a latching collar 27 surrounds the shell and engages in said cut away portion. A flat spring 28 passes through the collar 27 at the side opposite the cut away portion 26 and serves normally to hold the collar in such a position that one side of the collar is seated in the cut away portion as shown.

The upper edge 31 of the collar 27 cooperates with a shoulder 32 on the blade carrying

element 22 to latch the element in the inner position as shown in Fig. 3. When the element 22 is in the outer or cutting position the shoulder 32 engages the lower end of the interior of the handle 10 and the lower edge 33 of the collar 27 engages behind the end of the element 22 to prevent inward movement of the element.

In order to permit the blade carrying element 22 to move from one position to another, it is necessary to shift the collar 27 against the tension of the spring 28 to bring the interior of the collar in alignment with the corresponding portion of the interior of the shell 16. This movement of the collar is effected from the exterior of the handle by finger pressure applied to a rib 34 formed on the collar 27, or, preferably, formed in a small separate piece, as shown in Figs. 5 and 6, resting against the collar. In either construction the rib 34 projects outward through the opening 12 in the side of the handle far enough to permit shifting the collar 27 by finger pressure on the rib to release the blade.

The shell 16 and all other parts directly associated with the blade are so designed or shaped as to hold the blade against excessive angular movement with respect to the handle when the knife is used for cutting, although the parts cannot fit so tightly as to interfere with the sliding movement of the blade element.

From the foregoing it is thought that the construction and operation are clear, but it might be stated that to open the knife it is only necessary to hold it with the slot 11 downward and press upon the rib 34 to carry the upper edge of the collar 27 out of the path of the shoulder 32 and then release the collar to permit the spring 28 to return the collar to its original position, thereby bringing the lower edge of the collar above the end of the element 22. To close the knife it is held with the slotted end 11 upward and the rib 34 pressed inward to release the element 22 and permit it to drop back into the interior of the knife and be latched in the inner position when the rib 34 is released.

While the construction shown and described is admirably adapted to fulfill the purposes primarily stated, the invention is capable of various changes and embodiments, all coming within the scope of the claims which follow.

55 **What I claim is:—**

1. A device of the character described comprising a hollow handle provided with a slot in one of its ends, an element movable in the handle provided with a blade portion constructed to pass in and out through the slot and a projection co-operating with the interior of the handle adjacent the slot to limit outward movement of the blade, a guiding element within the handle surrounding the blade element and having a cut-away portion

in one of its sides, a latching collar surrounding the guiding element and working in said cut-away portion and co-operating with the blade element, a spring normally holding the latching collar in latching position, and means operable from the exterior of the handle opposite the aforesaid cut-away portion for moving the latching element against its spring to release the blade element.

2. A device of the character described comprising a hollow handle provided with a slot in one of its ends and an opening along one of its sides, an element movable in the handle provided with a blade portion constructed to pass in and out through the slot and having a projection co-operating with the interior of the handle adjacent the slot to limit outward movement of the blade, a guiding element within the handle limiting the blade element to endwise movement and having an opening in the side thereof opposite the aforesaid opening in the side of the handle, a latching element carried by the guiding element and co-operating through the opening in said guiding element with the blade element to latch the latter with the blade in either the inner or outer position with respect to the aforesaid slot, a spring normally holding the latching element in latching position, and means operable through the aforesaid opening in the handle to move the latching element against its spring to unlatch the blade element.

3. A device of the character described comprising the combination of a hollow handle provided with a slot in one of its ends, a blade movable in the handle and carrying a projection co-operating with the handle adjacent said slot to limit movement of the blade outward of the slot, a guiding element for the blade within the handle having a cut-away portion in one of its sides, a collar surrounding said element and cut-away portion and co-operating with the aforesaid projection to latch the blade within the handle and element and with the inner end of the blade to latch the blade in its outer or exposed position, a spring normally holding the collar in latching position, and means operable from the exterior of the handle to operate the collar to unlatch the blade.

4. A device of the character described comprising the combination of a hollow handle provided with a slot in one of its ends, an element movable in the handle provided with a blade portion constructed to pass in and out through the slot and a projection co-operating with the interior of the handle to limit outward movement of the blade, a guiding element for the blade element within the handle and having a cut-away portion in one of its sides, a collar engaging in said cut-away portion and surrounding the guiding element, one edge of said collar co-operating with the aforesaid projection to latch the

- blade in retracted position and the other edge with the inner end of the blade element to latch the element with the blade projecting through the aforesaid slot, a spring holding the collar normally in latching position, and means operable from the exterior of the knife handle for moving the collar against said spring to carry the latching edges of the collar out of latching position.
- 10 5. A device of the character described comprising a flat, hollow handle having a slot in one of its ends and an opening substantially half-way along one of its edges, a guiding element formed from a single sheet of metal 15 to conform to the shape of the interior of the knife handle and having a cut-away portion in the edge farthest from the opening in the handle, a flat collar having one side normally resting in the aforesaid cut-away portion, a spring between the opposite side of the collar and the guiding element serving to hold the collar in the cut-away portion, a 20 blade carrying element movable by gravity end-wise in the guiding element to carry the blade in or out through the end slot in the handle and provided with portions engageable by the part of the collar in the aforesaid cut-away portion to latch the blade in outer or inner position, and means operable 25 through the opening in the handle to shift the collar against its spring to carry the portion normally in said cut-away portion out of locking position to free the blade carrying element for movement.
- 30 6. A device of the character described comprising a flat, hollow handle having a slot in one of its ends, said end being tapered, a guiding element formed from a single sheet of metal within the handle having one end 35 wedged in the tapered end of the handle, a cap closing the other end of the handle and engaging an extension formed on the guiding element to hold the guiding element in position, said handle, cap and extension having aligned perforations, a bow engaging through said perforations in the handle, cap and extension on the guide to hold the parts specified together, a blade carrying element movable endwise in the guiding element, and 40 latching devices operable from the exterior of the handle for controlling movements of the blade carrying element.
- 45 In testimony whereof I hereto affix my signature.
- 50 BENJAMIN F. GRENNAN.
